GREETING CARD

Vera S. Neumann, Ossining, N. Y.

Application April 9, 1952, Serial No. 281,388

2 Claims. (Cl. 206—79)

This invention relates to a greeting card.

The application of this invention is to greeting cards of virtually every description, such as Christmas cards, birthday cards, anniversary cards and the like. For purposes of illustration, however, the invention will herein be described solely in terms of its relation to Christmas cards. But this should not be construed as limiting the invention in any way whatsoever.

The principal object of this invention is the provision of a greeting card which incorporates as a detachable component part thereof a useful article, such as a tie or scarf or other article of wearing apparel or any accessory thereto or any other article which is useful apart from its connection with the greeting card. When the article is mounted on the greeting card, it constitutes an integral part thereof in the sense that it completes or supplements the message, greeting or other material which appears on the card. Stated differently, the greeting or message or other material which appears on the card is not complete without the detachable article above mentioned.

In the illustrated form of this invention, a Christmas card is provided and on said Christmas card is the picture or representation of a fireplace and Santa Claus. The major part of the fireplace and the visible part of Santa Claus are printed or otherwise permanently applied directly to the card. The remaining part of the fireplace and Santa Claus' hat are formed by the very material of which the detachable article is itself made. In the illustrated case, the fireplace is built of simulated bricks and the detachable article is a tie or narrow scarf which is imprinted with a brick pattern or design corresponding in appearance to the brickwork of the fireplace. The ends of the tie or narrow scarf are tapered and tasselled and they are disposed atop the head of Santa Claus to represent the crown of his hat. When the tie or scarf is removed from the card, the fireplace is incomplete and so is the hat which Santa Claus wears. Thus the greeting card is incomplete without the tie or scarf mounted thereon. However, when the tie or scarf is removed from the card, it constitutes a complete and useful entity in itself and may be worn on the person in precisely the same manner as any other tie or scarf of like character which is made solely for wearing purposes and devoid of any connection with a greeting card.

A preferred form of this invention is shown in the accompanying drawing in which:

Fig. 1 is a face view of Christmas card made in accordance with this invention, said Christmas card being unfolded and disposed in open position.

Fig. 2 is a longitudinal section through said open Christmas card, said section being taken on the line 2—2 of Fig. 1.

Fig. 3 is a side edge view of the same Christmas card showing it folded over into closed position.

It will be seen in the drawing that the greeting card herein described and claimed comprises two basic ele-

2

ments: a greeting card proper 10 and a useful article of manufacture 12. In the illustrated form of this invention, the greeting card is intended for use during the Christmas holiday season and it embodies the theme of Santa Claus climbing down the chimney and emerging from a fireplace. This, of course, is purely illustrative of the invention and it should not in any sense whatsoever be regarded as limiting the invention to its illustrated form. The useful article of manufacture in the 10 illustrated form of the invention is a narrow scarf or tie of the type which women tie around their necks. This too should be understood as illustrating, rather than limiting, the invention. The pictorial representation 14 which is printed on or otherwise applied to the greeting 15 card is that of an incomplete brick fireplace and the upper end of the fireplace may be imaginatively viewed as constituting the chimney to which said fireplace is connected. There is also a pictorial representation 16 of Santa 20 Claus and the two pictorial representations are juxtaposed so as to give the impression of Santa Claus descending or ascending the combined fireplace and chimney.

The fireplace is incomplete in the sense that a narrow vertical strip 18 appears to be missing therefrom as Fig. 1 clearly shows. The pictorial representation of 25 Santa Claus is incomplete in the sense that his body appears to be hidden behind the fireplace and also in the sense that his hat is without a crown.

The narrow scarf or tie 12 has the pictorial representation of brickwork printed thereon or applied thereto 30 in any conventional manner. The brickwork of the tie and the brickwork of the fireplace correspond to each other in appearance so that the brickwork of the tie may be employed to supplement or complete the brickwork of the fireplace in the manner shown in the drawing. 35 More specifically, greeting card 10 is provided with three parallel slits 20, 22 and 24 formed therein in spaced relation to each other. Looped through slits 22 and 24 and projecting upwardly through slit 20 is the tie 12. It will be seen that the tie covers the blank space 18 which renders the fireplace incomplete. Since the brickwork on the tie corresponds to the brickwork of the fireplace, the incomplete portion of the fireplace is covered over in such manner as to provide the impression of being complete. Thus the tie is an integral 40 part of the fireplace since without the tie the fireplace is incomplete.

The two ends 12a and 12b of the tie are tapered to a point and tassels 26 are tied or sewn loosely thereto. These tapered and tasselled ends of the tie project upwardly through slit 20 and thereby extend above that portion of the hat 28 which lies below the crown. There is no representation of a crown, however, on the greeting card and these upwardly extending ends of the tie take its place. They strongly resemble the crown of a hat that Santa Claus is usually represented as wearing and hence they function on the card to complete the hat.

The greeting card 10 may be made of any suitable material of the type used by the greeting card industry.

60 A stiff grade of paper would be very suitable for this purpose but other materials are also useful in this connection. The tie or scarf 12 may also be made of any suitable tie or scarf material, such as silk, rayon, nylon, cotton and similar fabrics. The pictorial representations on the greeting card and on the tie may be applied thereto by any conventional means and method. For example, screen printing and other printing methods may be employed for this purpose.

70 The greeting card may be mailed in the form shown in Fig. 1. It is more convenient, however, to fold it over on line 30 as shown in Fig. 3 and to mail it out in folded condition. This helps protect the tie and it

also endows the greeting card with the form of a book whose secret is contained between its covers. After the greeting card performs its function as a greeting card, the tie may be slipped out of the slits through which it is looped and it may then be used as an article of wearing apparel.

The foregoing illustrates one form of this invention. This illustrative form may be modified in many ways and other forms may be provided within the broad spirit of the invention and the broad scope of the claims. For example, speaking only of the illustrated form, it will be noted that the tie is folded over double before it is threaded through the slits of the greeting card. This is one way of attaching the tie to the card but there are other ways too. However, the invention is not limited to a tie, irrespective of whatever way it is secured to the greeting card. Other articles of wearing apparel and other useful articles of manufacture may be substituted for the tie and they may be attached to greeting card either by threading them through slits as shown in the drawing or by any other suitable means and method. The pictorial representations both on the greeting card and on the useful article secured thereto are matters of choice and preference is not limited to the representation of Santa Claus and a fireplace.

I claim:

1. A greeting card having a useful article of manufacture detachably secured thereto, said greeting card having an incomplete, interrupted pictorial representation printed thereon and said article comprising a narrow scarf for women which is adapted to be worn around the neck, said card having a plurality of slits formed therein and said narrow scarf being drawn through said slits and being wound around at least one portion of the card between at least two of said slits in order to secure said narrow scarf to said card, said narrow scarf having a complementary pictorial representation printed thereon which completes the incomplete pictorial representation of the card when said narrow scarf is mounted thereon and gives it continuity, said slits being three in number and being in spaced parallel relation to each other, said narrow scarf being doubled upon itself and being drawn through the uppermost slit from the front to the back of the card and then down to the intermediate slit and through said intermediate slit to the front of the card and then down to the lowermost slit and through

5 said lowermost slit to the back of the card and then upwardly to and through the intermediate slit to the front of the card.

2. A greeting card having a useful article of manufacture detachably secured thereto, said greeting card having an incomplete, interrupted pictorial representation printed thereon and said article comprising a narrow scarf for women which is adapted to be worn around the neck, said card having a plurality of slits formed therein and said narrow scarf being drawn through said slits and being wound around at least one portion of the card between at least two of said slits in order to secure said narrow scarf to said card, said narrow scarf having a complementary pictorial representation printed thereon which completes the incomplete pictorial representation of the card when said narrow scarf is mounted thereon and gives it continuity, said slits being three in number and being in spaced parallel relation to each other, said narrow scarf being doubled upon itself and being drawn through the uppermost slit from the front to the back of the card and then down to the intermediate slit and through said slit to the front of the card and then down to the lowermost slit and through said lowermost slit to the back of the card and then upwardly to and through the intermediate slit to the front of the card, the incomplete representation on the card being that of an incomplete brick fireplace and a pictorial representation of Santa Claus, the narrow scarf bearing the pictorial representation of fireplace brick-work which completes the incomplete fireplace on the card, the upwardly projecting end of the narrow scarf which projects across the front of the card immediately adjacent the uppermost slit being tapered to a point to simulate a hat for Santa Claus.
